FOOT TOOL

Beecher Zeblin Furr, Robert C. Furr, and
Marion O. Harrill, Jr., Charlotte, N. C.

Application October 29, 1953, Serial No. 388,948

5 Claims. (Cl. 97—61)

The present invention relates to an improved foot tool adapted to be removably attached to the shoe and more particularly to a foot tool adapted for use in gardening and allied arts which is so constructed to permit easy interchange of attachments to permit the tool to be adapted for a number of different gardening operations such as, for example, weeding, cultivating, planting and the like.

In the past most non-machine gardening operations have generally been carried out with hand tools such as hand hoes, cultivators, dibbles and the like even though there have been a number of suggestions to provide attachments for shoes so that such operations might be performed by foot power and that a number of gardening operations can be easily and comfortably performed by foot power. The foot tools which previously have been suggested have been primarily designed for only one gardening operation and, consequently were rather bothersome to use when different gardening operations were to be carried out alternately or sequentially by the same person.

It is an object of the present invention to provide a novel tool holder for attachment to a shoe and to which a number of tools may be interchangeably attached in a simple and facile manner.

It is a further object of the present invention to provide a foot tool holder adapted and arranged to permit easy interchangeable attachment of tools without the necessity of complete removal of the holder from the shoe.

The foot tool according to the invention comprises a holder to which a number of individual tools can be interchangeably attached. The holder is generally shaped to conform to the shape of the foresole of a shoe and is adapted to be secured under the foresole of a shoe, for example, by means of straps passing over the shoe. The holder, preferably on its underside, is provided with means adapted to receive the individual interchangeable tools, and means are provided on such holder cooperating with the shoe sole so as to lock the individual interchangeable tool securely in place as long as the holder is held snugly against the bottom of the shoe sole, but upon loosening of the holder from its position against the shoe sole will permit easy withdrawal and interchange of the individual tools.

The accompanying drawings show, by way of example, several views of a tool holder according to the invention and several forms of interchangeable tool attachments for use in conjunction with such holder.

In the drawings:

Fig. 1 is a side view of a tool holder according to the invention partially secured to a shoe with an interchangeable tool in position to be locked in place.

Fig. 2 is a sectional view of the tool holder shown in Fig. 1 when fully secured to a shoe with the interchangeable tool locked in place.

Fig. 3 is a side view of the tool holder shown in Fig. 1 fully secured to a shoe with another interchangeable tool locked in place.

2

Fig. 4 is a top view partially in section of the tool holder and interchangeable tool shown in Figs. 1 and 2.

Fig. 5 is a top view partially in section of the tool holder with interchangeable tool shown in Fig. 3 shown in dotted lines.

Figs. 6 and 7 show two further modifications of interchangeable tools for use with the tool holder.

Referring to Figs. 1, 2 and 4 of the drawings, the curved bottom plate 1 of the tool holder generally conforms to the shape of a foresole of a shoe and is adapted to be strapped to the shoe 2 of the operator by straps 3 and 4. Interchangeable tool 5, which in this instance is a substantially flat blade having its forward end which extends beyond the shoe sharpened to permit weed cutting and/or hoeing action, is carried by its shank in U-shaped members 6 and 7 projecting below plate 1 and locked in position by pin 8 which passes through hole 9 in plate 1 and then through hole 10 in such tool. Pin 8 is carried by resilient member 11 which normally urges such pin upwardly and out of engagement with hole 9 as shown in Fig. 1, but when the holder is drawn up snugly against the sole of the shoe as shown in Fig. 2, it will be pressed downwardly by the shoe sole and pass through hole 10 in the tool and lock the tool carried by members 6 and 7 in position.

An upwardly projecting front end 21 is provided on plate 1 which not only protects the toe of the shoe of the operator during use of the foot tool, but also prevents the plate from sliding backwards during use of the tool.

A further U-shaped member 12 is provided towards the rear of plate 1 which in conjunction with U-shaped member 7 can serve to receive a differently shaped interchangeable tool which is better adapted for use when it is held rearwardly from the front end of plate 1, such as, is, for example, shown in Figs. 3 and 5, wherein a coring tool 13 is held by U-shaped members 7 and 12 against the bottom of the rearward end of plate 1. In this instance the tool 13 is also locked in position by pin 8 which passes through hole 10 in a shank of such tool.

U-shaped members 6, 7 and 12 as shown can be formed integrally with plate 1 by providing substantially parallel pairs of slits and depressing the metal strip therebetween to form the U-shaped members. It is, of course, possible, if desired, to form such U-shaped members from a separate piece of metal and attach their free ends to plate 1. Furthermore, it is within the purview of the invention to provide other equivalent means than U-shaped members for receiving the individual interchangeable tools which are to be locked in place by pin 8, it only being necessary that such means permit a portion or portions of the tool to be held thereby against the bottom of plate 1, but permit withdrawal or insertion of the tool when such tool is not locked in position by pin 8.

Fig. 6 shows an interchangeable tool 14 of modified form which is suitable for cutting and weeding operations. In this instance the tool is provided with cut out portions 15, 16 and 17 so as to provide tongues 18 and 19 which can be slid into U-shaped members 6 and 7 to permit the tool to be locked in position by pressing pin 8 through hole 10 provided therein.

Fig. 7 shows another interchangeable tool 20 adapted for cultivating purposes. Such tool, similar to the tool shown in Figs. 1, 2 and 4, has a shank which can be passed through U-shaped members 6 and 7 and be locked in position by pressing pin 8 through hole 10 provided therein.

As can be seen from Figs. 1 and 2, the foot tool according to the invention permits easy attachment and interchange of the individual tools on the holder provided without the necessity of removing the holder completely from the shoe of the operator. For insertion or interchange of a tool it is, for example, merely necessary to

loosen the forward strap 3 of the holder to relieve the pressure of the shoe sole against resilient member 11 so that pin 8 is automatically drawn upwardly out of locking position by such resilient member, so as to permit withdrawal of any tool which may already have been held by the holder, then inserting another tool in the appropriate U-shaped members 6 and 7 or 7 and 12 and finally tightening strap 3 so that the shoe sole presses resilient member 11 and pin 8 carried thereby into locking position.

We claim:

1. In a foot tool, a tool holder, means for removably attaching such tool holder snugly against the bottom of a sole of a shoe, means on said tool holder for removably attaching individual tools to said holder, said last-named means including a resilient member carried by the tool holder, a detent carried by such resilient member, said resilient member and detent cooperating with the bottom of the shoe sole for locking the individual tool in position when said tool holder is attached snugly against the bottom of the shoe sole and releasing such tool when at least a portion of said tool holder is moved out of snug engagement with the bottom of the shoe sole.

2. In a foot tool, a tool holder comprising a plate member conforming generally to the shape of the fore-sole of a shoe, means for removably attaching said plate member snugly against the bottom of the sole of the shoe, means on said plate member for removably attaching individual tools thereto, said last-named means including retaining means for holding the individual tools against the bottom of the plate member, but permitting withdrawal and insertion of the individual tools therein, a resilient member carried by the tool holder, and a detent carried by such resilient member, said resilient member and detent cooperating with the bottom of the shoe sole for locking the individual tool held by said retaining means in position when said plate member is attached snugly against the bottom of the shoe sole and releasing such tool so that it can be withdrawn from said retaining means when at least a portion of said plate member is moved out of snug engagement with the bottom of the shoe sole.

3. In a foot tool, a tool holder comprising a plate member conforming generally to the shape of the fore-sole of a shoe, means for removably attaching said plate member snugly against the bottom of the sole of the shoe, means on said plate member for removably attaching individual tools thereto, said last-named means including a plurality of U-shaped retaining means extending downwardly from the bottom of the plate member adapted to receive and hold the individual tool against the bottom of the plate member, but permitting withdrawal and insertion of the individual tool therein, a resilient member carried by the tool holder and a detent carried by such resilient member, said resilient member and detent cooperating with the bottom of the shoe sole for locking the individual tool held by said retaining means in position when said plate member is attached snugly against the bottom of the shoe sole and releasing such tool so that it can be withdrawn from said retaining means when at least a portion of said plate member is moved out of snug engagement with the bottom of the shoe sole, said resilient member normally urging said detent out of locking position.

4. A tool holder according to claim 3, in which said plate member carries at least three of said U-shaped retaining means of which two are on the forward end of such plate and one is on the rearward end of said plate.

5. A tool holder according to claim 3, in which said plate member has an upwardly turned flange at its forward end.
